UNITED STATES PATENT OFFICE.

EDWARD A. JOHNSTON AND CARL W. MOTT, OF CHICAGO, ILLINOIS, ASSIGNEES TO
INTERNATIONAL HARVESTER CORPORATION, A CORPORATION OF NEW JERSEY.

POWER-OPERATED PLOW.

1,121,844.

Specification of Letters Patent. Patented Dec. 22, 1914.

Application filed August 20, 1913. Serial No. 785,798.

To all whom it may concern:

Be it known that we, EDWARD A. JOHNSTON and CARL W. MOTT, citizens of the United States, and residents of Chicago, in the county of Cook and State of Illinois, have invented certain new and useful Improvements in Power-Operated Plows, of which the following is a full, clear, and exact specification.

10 This invention relates to plows, and particularly to power operated plows adapted to be operated automatically and manually.

One of the objects of this invention is to render it possible for individual plows to 15 be controlled automatically and manually under all conditions and in the proper order to meet the requirements for successful commercial operation.

A further object of our invention is to 20 render possible the manual control of plows in connection with means used for automatically operating said plows.

These objects are accomplished by providing in a gang plow an arrangement 25 whereby the individual plows may be raised and lowered automatically, and means for operating or varying manually the depths of said individual plows.

The invention is illustrated on the accompanying sheets of drawings, in which—

Figure 1 is a plan view of a gang plow embodying our invention; Fig. 2 is a fragmentary side elevation of the same gang plow; Fig. 3 is a sectional view, parts being in elevation, taken in the plane of line 3—3 of Fig. 2; Fig. 4 is a detail plan view of a portion of the automatic control mechanism used in the operation of the plows; Fig. 5 is a similar view of the same, more 40 parts being shown in detail; Fig. 6 is a sectional view of a portion of the automatic control mechanism taken along the planes of irregular line 6—6 of Fig. 1; and, Fig. 7 is a detail plan view of two members 45 forming parts of the control mechanism.

The various novel features of our invention will be apparent from the description and drawings, and will be particularly pointed out in the appended claims.

50 Our invention is disclosed in connection with a gang plow having a frame 10 including two side members 11 and 12, a front member 13 and a back member 14 extending diagonally between the frame members 11 and 12. This frame also includes support-

ing and bracing bars 14 which extend longitudinally of the frame and parallel with the sides thereof. This substantially triangular frame of the gang plow is mounted and runs on three wheels 15, 16 and 17, the first mentioned wheel 15 being provided with a corrugated rim and having a shaft 18 journaled in a bracket member 19 secured to one of the side frame members 12. The other front wheel 16 is mounted on a crank shaft 20 upon which is mounted a worm gear 21 meshing with a worm 22 on a shaft 23 having a squared end 24 by means of which said worm 22, gear 21, and crank shaft may be operated for raising and lowering the front portion of the gang plow frame. The back wheel 17, which is a caster wheel, is carried in a supplementary frame member 26 which is pivotally mounted on a rod 27. Mounted in said frame member 26 is one portion of a similar crank shaft 25, the opposite end of said shaft 25 being slidably mounted in a grooved portion 28 of the side frame member 11. By means of a lever 29, the back part of the frame of the gang plow may be raised and lowered, a spring 30 being of assistance in raising the gang plow frame. The frame is provided with suitable members 10^a by means of which the gang plow may be connected to a traction engine.

Pivotally mounted in the gang plow frame is a series of plow beams 31, 32, 33 and 34 carrying respectively plows 35, 36, 37 and 38. Fastened to the plow beams in advance of the plows are the usual colter wheels 31^a. Secured to the back end of each of the plow beams is one end of a chain, connector or resilient member 39, the other end of each of which is secured to a cam actuated member, the chains or resilient members connected respectively to plow beams 31, 32, 33 and 34 being connected to the cam actuated members 40, 41, 42 and 43 respectively. Each of the chains 39 passes over or around a shiftable or movable pulley 44 and a relatively stationary pulley 45, the latter being mounted in a bracket 46 which is secured to the diagonally arranged frame member 14. The movable pulley 44 is mounted in one end of an actuating lever 47 having a detent 48 adapted to engage notches 49 in the bracket 46 to hold the plow in any adjusted position. As shown in Fig. 2, it is apparent

that by moving the hand end of the lever 47 downwardly, the movable pulley 44 will be elevated, thus raising the plow 35, and if it is desired to lower the plow, the same 5 may be accomplished by raising the lever 47. In like manner all of the plows 35, 36, 37 and 38 may be controlled manually for raising and lowering said plows individually. Secured to the frame is a series of 10 spaced vertically arranged guide members 14^a between which portions of the respective plow beams are raised and lowered and prevented from being shifted laterally.

For raising automatically in proper succession the individual plows, for example, at the end of a furrow, preparatory to turning, and for lowering automatically said plows in proper succession after a turn has been effected, the following mechanism is 15 employed: Mounted upon one end of the shaft 18 (see Fig. 3), journaled in bearings 50 formed in a depending bracket 51, secured to a frame of the gang plow, is a bevel gear 52 meshing with a larger bevel gear 53, secured to one end of a vertical shaft 54, journaled in the sleeve member 55 of the bracket 51. Secured to the upper portion of shaft 54 is a notched wheel 56, the notches of which are adapted to be engaged 20 under certain conditions by a pawl member 57 having a roller 58 mounted in one end thereof. This pawl is pivotally mounted (see Figs. 1, 4, 5 and 6) in a flanged portion 59 of a cam member 60, the latter of which is 25 mounted loosely upon the vertical shaft 54. Secured to the pin 61, to which pawl 57 is fixed, is a collar member 62 having oppositely arranged ears 63 with depending projections 64 and 65 respectively, the former of which projections is located in an elongated notch or opening formed by a projection 66 and a shoulder portion 67 of a dog 68, said dog being pivotally mounted loosely 30 upon the lower part of pin 61. A spring 69 which connects an arm 70 on the projection 66 tends to swing the dog 68 inwardly into the position shown in dotted lines in Fig. 35. Said dog is normally held against the tension of said spring in the full line position shown in said figure, by either one of two adjustable fingers 71 and 72 mounted upon a spindle 73 movably mounted in the plow frame and having a handle or lever 74 held by a spring 75 to hold normally the 40 fingers 71 and 72 in an upward position to prevent the dog 68 from swinging inwardly. By swinging the lever 74 upwardly, as viewed in Fig. 1, and to the right, as viewed in Fig. 6, the finger 71 will be rotated or 45 lowered out of the path of the dog 68 whereupon, due to the action of the spring 69, the dog 68 will be swung inwardly. During this inward movement the projection 66 of the dog 68 passes into engagement with the 50 depending projection 64 of collar 62, ro-

tating said collar, shaft 61 and consequently pawl 57 into the full line position shown in Fig. 4, the roller 58 of the pawl engaging one of the notches in the notched member 56. Due to the fact that this notched member 56 is rotated by means of its connections through shaft 54, gears 53 and 52 and shaft 18 whenever the gang plow is in motion, the cam member 60, with the pawl engaging a notch in the notched member 56, will be actuated to respectively and successively engage the arms 76, 77, 78 and 79 of the actuated members 40, 41, 42 and 43 to raise the plows 35, 36, 37 and 38 respectively through the medium of their chains. After the 55 power operated cam member has raised all of the plows by engaging the automatically actuated members 40, 41, 42 and 43, and said cam member is still in engagement with the arms of said actuated members, the said cam member 60 is stopped automatically by means of finger 72, which had again risen with finger 71 as soon as the lever 74 was released, engaging one side 80 of the dog 68 and gradually forcing said dog into its 60 outward position, as shown in dotted lines in Fig. 4. As the dog member 68 is being swung outwardly gradually, it swings freely upon the stem 61, imparting no motion to the pawl member 57 until the shoulder portion 67 of said dog member 68 moves into engagement with the depending projection 64 on the collar member 62 which is secured to shaft 61. At the instant said dog member 65 engages said depending projection 64 a compressed spring 81, held between projection 65 of collar 62 and projection 82 on the dog member 68, liberates sufficient force to snap the pawl 57 out of engagement with one of the notches of the notched member 56, 70 whereupon further movement of cam member 60 is arrested. With the cam member 60 in dotted line position shown in Fig. 4, the plows are raised. If it is desired to lower said plows automatically and successively, as, for instance, having turned preparatory to plowing in another direction, the hand lever 74 is again swung to lower the finger 72 out of the path of the dog member 68, whereupon, as above explained, the roller 75 75 of pawl member 57 will be swung into engagement with one of the notches of the notched member 56. Due to the fact that said notched member 56 is continuously rotating whenever the gang plow is in motion, the cam member will be rotated farther in a clockwise direction successively passing out of engagement with the automatically actuated members 40, 41, 42 and 43, permitting the plows 35, 36, 37 and 38 to successively drop, due to their own weight, said automatically actuated members 40, 41, 42 and 43 being limited in their movements by stops 85. In like manner, after the cam member 80 has passed out of engagement with said au- 125

tomatically actuated members 40 to 43 inclusive, the pawl 57 will be thrown out of engagement with the notched member by the coöperation of the dog member 68 and finger 71.

It is apparent from the above that the individual plows in the gang may be raised and lowered automatically in proper succession, and due to the diagonal arrangement of the plows and the relative spaced intervals of operation of said plows through the automatically actuated members 40, 41, 42 and 43, the plows will all be raised in a manner so that the end of the furrows made by the individual plows will be in a line perpendicular to the line of draft, plow 35 being raised first, then successively plows 36, 37 and 38. In the same succession the plows will be lowered, the beginning of the furrows made by said plows being in a line perpendicular to the line of draft. With the plows all sunk in the ground and in the operation of plowing, it will be seen that the depths of the plows may be controlled manually and individually by operating the hand levers 47 which effect a movement of the plows through the pulleys 44 and 45 and the chains 39. It is to be observed that said pulleys and chains are used both in the automatic and manual operation of the plows. With this simple arrangement the plows may be raised and lowered automatically at will, and the depths of the plows manually controlled to meet the requirements. For instance, if an obstruction of some kind is in the path of any one of the individual plows, that particular plow could be raised out of the ground without raising all of the plows, and then lowered again after the obstruction had been passed. Other advantages also are apparent.

It is evident that there may be various modifications of our invention other than that herein particularly shown and described, and it is our intention to cover all such modifications which do not involve a departure from the spirit and scope of our invention, as set forth in the appended claims.

What we claim as our invention and desire to secure by Letters Patent is:—

1. In combination, a plow, means for automatically raising and lowering said plow, and separate means for manually raising and lowering said plow independently whether or not said plow is being raised or lowered automatically.

2. In combination, a plow, means for automatically raising and lowering said plow, and separate means associated with said automatically raising and lowering means for manually raising and lowering said plow independently whether or not said plow is being raised or lowered automatically.

3. In combination, a plow, a connection through which said plow is raised and lowered automatically, and manually controlled means separate from and associated with said connection for raising and lowering said plow independently whether or not said plow is being raised or lowered automatically.

4. In combination, a pivotally mounted plow, automatic means for raising and lowering said plow, and independent manually controlled means associated therewith for also raising and lowering said plow independently whether or not said plow is being raised or lowered automatically.

5. In combination, a plurality of pivotally mounted plows, flexible members associated with said plows, automatically actuated members to which said flexible members are connected for automatically controlling the operation of said plows in predetermined succession, and means adjustably connected with said flexible members for operating said plows manually.

6. In combination, a plurality of plows, automatically actuated members for controlling the operation of said plows, connections between said automatically actuated members and the individual plows, and a single cam for actuating said automatically actuated members in a predetermined succession.

7. In combination, a plurality of plows, separate automatically actuated members for controlling the operation of said plows in a predetermined succession, connections between said members and said plows, and a single cam through which said automatically actuated members are actuated.

8. In combination, a plurality of plows, separate automatically actuated members for controlling the operation of said plows in a predetermined succession, connections between said members and said plows, a single cam through which said automatically actuated members are actuated, and manually actuated means for raising and lowering said plows individually.

9. In combination, a plurality of plows, automatically actuated members for actuating the individual plows, a single cam for actuating said automatically actuated members, and means for controlling the operation of said cam.

10. In combination, a plurality of pivotally mounted plows, a plurality of individually operated members operatively connected to said plows, a single cam for operating said individually actuated members, and means for controlling said cam.

11. In combination, a plurality of pivotally mounted plow beams, plows carried thereby, separate automatically actuated members, connections between said members and said plow beams, a single cam for actuating said separate members for raising and

- lowering said plows, an actuator for said cam, and a detachable connection between said actuator and said cam for controlling the operation of said plows.
5. 12. In combination, a plurality of pivotally mounted plow beams, plows carried thereby, separate automatically actuated members, connections between said members and said plow beams, a single cam for actuating said separate members for raising and lowering said plows, an actuator for said single cam, a detachable connection between said actuator and said single cam for controlling the operation of said plows, and 10 manually operated members associated with said connections for raising and lowering said plows individually.
13. In combination, a plurality of plows, means including automatically actuated 20 flexible members for raising and lowering said plows, and separate members connected with said flexible members for raising and lowering said plows manually and individually whether or not said flexible members 25 are being actuated automatically.
14. In combination, a pivotally mounted plow beam, a plow carried by said plow beam, an automatically actuated flexible member connected to said beam for raising 30 and lowering said plow, and a manually operated member connected to said flexible member for giving said plow an independent raising and lowering movement whether or not said flexible member is being actuated automatically.
15. In combination, a plow, an automatically actuated member for operating said plow, and an independent manually controlled member associated therewith for giving said plow an additional operative movement whether or not said automatically actuated member is being actuated.
16. In combination, a plow, an automatically actuated member for operating said 45 plow, a connection between said member and said plow, and separate means connected with said connection for giving said plow an additional operative movement whether or not said automatically actuated member 50 is being actuated.
17. In combination, a plurality of plows, means for operating said plows automatically in a predetermined succession, and means adjustable with respect to said other 55 means for operating one of said plows at any time independent of automatic operation.
18. In combination, a plurality of plows,
- means for operating said plows automatically in a predetermined succession, and 60 means adjustable with respect to said other means for operating any one of said plows at any time independent of automatic operation.
19. In combination, a plurality of plows, 65 means for operating said plows automatically in a predetermined succession, and means adjustable with respect to said other means for operating any one of said plows manually at any time independent of automatic operation.
20. In combination, a plow, means for raising and lowering said plow automatically, and means for raising and lowering said plow manually, the action of either of 70 said means giving a separate raising or lowering movement to said plow whether or not both of said means are effective simultaneously.
21. In combination, a plow, means for 75 raising said plow automatically, and means for raising said plow manually, the action of either of said means giving a separate raising movement to said plow whether or not both of said means are effective simultaneously.
22. In combination, a plow, means for lowering said plow automatically, and means for lowering said plow manually, the action of either of said means giving a 80 separate lowering movement to said plow whether or not both of said means are effective simultaneously.
23. In combination, a plurality of pivotally mounted plows, means for automatically raising said plows in a predetermined 85 succession, and a hand operated regulator for said means.
24. In combination, a plurality of movably mounted plows, means for automatically actuating said plows, and a hand operated regulator for said means.
- 100 25. In combination, a plow, means for automatically actuating said plow, and a hand operated regulator for said means.
26. In combination, a frame, a plow supported thereby, means for automatically actuating said plow relative to said frame, and a regulator for said means.
